A. HERZINGER.

HEATER.

APPLICATION FILED MAR. 20, 1915.

Patented Dec. 28, 1915.

UNITED STATES PATENT OFFICE.

ANTON HERZINGER, OF PLAINVIEW, NEBRASKA.

HEATER.

1,166,372.

Specification of Letters Patent. Patented Dec. 28, 1915.

Application filed March 20, 1915. Serial No. 15,829.

To all whom it may concern:

Be it known that I, ANTON HERZINGER, a citizen of the United States, residing at Plainview, in the county of Pierce and State 5 of Nebraska, have invented certain new and useful Improvements in Heaters; and I do hereby declare the following to be a full, clear, and exact description of the invention, such as will enable others skilled in the art 10 to which it appertains to make and use the same.

This invention has for its object to provide a simple and efficient heater especially designed for heating the liquid contents of 15 a tank or the like.

Another object is the provision of a tank heater including a casing adapted to be partly submerged in a liquid to be heated and containing a preferred type of burner 20 associated with a heating drum of hollow formation communicating with pipes extending through the casing.

With these and other objects in view, the invention consists in the novel construction, 25 arrangement and formation of parts as will be hereinafter specifically described, claimed and illustrated in the accompanying drawing, in which:

Figure 1 represents a vertical central sectional view through the heater. Fig. 2 represents a top plan view thereof, partly in section.

Referring to the drawing in detail, wherein similar reference numerals designate 30 corresponding parts throughout the several views, the numeral 5 indicates the casing of the heater which may be of polygonal or cylindrical formation, as desired, and includes an imperforate bottom 6 and a removable top or cover 7. An air intake 35 pipe 8 is secured externally of the casing 5 and is provided with an angularly directed lower extremity 9 extending into and communicating with the interior of the casing 40 whereby air is supplied to the burner. Air outlet pipes 10 are arranged within the casing 5 and communicate with apertures formed in the cover 7 to permit the products of combustion to escape. A drum 11 of 45 hollow formation and preferably annular in shape is suitably supported in spaced relation above the bottom 6 of the casing and communicates with outwardly directed inlet and outlet pipes 12 and 13, respectively, de-

signed to conduct the water to and from the 55 drum 11. The water inlet pipe 12 is arranged in a lower horizontal plane than the outlet pipe 13 so as to insure proper circulation of the water through the drum during 60 operation of the heater. A burner 14 is supported upon the bottom 6 beneath the drum 11 and is adapted to be supplied with a suitable liquid fuel contained in the tank 15 by a fuel pipe 16. Pairs of crossed and 65 communicating water pipes 17 are secured at their ends in the inner vertical wall of the drum 11 and communicate with the water chamber 18 in the latter to accelerate heating of the liquid contents thereof. A deflector plate 19 is arranged over the drum 11. 70

In use, the casing 5 is partially submerged in water contained within a suitable tank, not shown, in such position that the cover and air inlet pipe 8 are disposed above the surface of the water. The water in the tank 75 is admitted to the drum 11 through the inlet pipe 12 and is discharged after it has been heated by the burner 14, through the pipe 13, and thus the water contained within the tank is circulated through the drum 11 until 80 thoroughly heated.

What I claim is:

A tank heater comprising a casing, a removable cover for said casing, an air pipe 85 extending through the lower portion of said casing and upwardly along the side wall thereof, a burner arranged in said casing, a fuel pipe supported in and extending exteriorly above said casing and connected with said burner, a hollow annular drum 90 disposed in said casing above said burner, outlet pipes for the products of combustion communicating with the interior of said casing near the bottom thereof and extending upwardly through said cover, water inlet 95 and outlet pipes connected with said drum and extending exteriorly of said casing, a circular deflector plate supported above and concentrically with relation to said annular drum, and crossed water pipes arranged internally of and connected with said drum. 100

In testimony whereof I affix my signature in presence of two witnesses.

ANTON HERZINGER.

Witnesses:

JOHN WOSTREL,
Ross A. Mote.
